UNITED STATES PATENT OFFICE.

ROBERT BAYLES ARMSTRONG AND GEORGE PATERSON, OF NEWCASTLE-UPON-TYNE, ENGLAND, ASSIGNORS TO R. & W. HAWTHORN, LESLIE & COMPANY, LIMITED, OF NEWCASTLE-UPON-TYNE, ENGLAND, AND COCKBURNS LIMITED, OF CARDONALD, NEAR GLASGOW, SCOTLAND.

VALVE DEVICE.

1,402,718.

Specification of Letters Patent.

Patented Jan. 3, 1922.

Application filed August 21, 1920. Serial No. 405,125.

To all whom it may concern:

Be it known that we, ROBERT BAYLES ARMSTRONG and GEORGE PATERSON, both subjects of the King of the United Kingdom of Great Britain and Ireland, and residing at Newcastle-upon-Tyne, England, have invented a certain new and useful Improvement in Valve Devices, (for which I have filed application in Great Britain June 17, 1918, Patent No. 128,373,) of which the following is a specification.

This invention relates to a valve device including two operatively connected valve elements proper engageable with separate seats and controlling separate passages, through one of which passages flows superheated steam and through the other of which flows saturated steam, whereby to control the proportions of superheated and of saturated steam to be admitted to steam engines, etc., without interference with the continuity of circulation through the superheater elements when maneuvering with the main engines for example.

The device according to the invention comprises a balanced valve system in which there is a double beat valve having provision to ensure maintenance of balance of the valve while taking account of inequalities of the amounts of superheated steam and saturated steam to be passed, as hereinafter more fully described.

Figs. 1 and 2 of the accompanying drawings are vertical sections of valve devices embodying the invention.

Figs. 1 and 2 illustrate constructions each comprising a double beat valve operating in a casing 1 having separate inlets 2 and 3 communicating respectively with a source of superheated steam supply and with a source of saturated steam supply, one beat 4 controlling the passage of superheated steam

and the other beat 5 controlling the passage of saturated steam.

To permit maintenance of the balance of such double beat valve, the valve elements 4, 5 are of substantially equal area; in order, however, to take account of the circumstance that the quantity of superheated steam to be passed may be different from the quantity of saturated steam to be passed, one of the beats, say the beat 4, or one of the seat portions, say the seat portion of the valve opening for superheated steam, may be provided with an apron 6, as shown in Fig. 1, or an apron 6', as shown in Fig. 2, serving more or less to constrict the relative passage, it being understood that the steam passed through each valve opening is proportional to the clear area, so that less steam will pass through a constricted opening than through an unconstricted opening.

We claim:

A valve system for controlling the proportions of super-heated and saturated steam to be admitted to steam engines, comprising the combination of a double beat valve including valve elements of substantially equal area controlling passages for superheated steam and saturated steam respectively leading thereto, and means including an apron constricting one of the passages whereby to insure maintenance of balance of said valve with unequal amounts of super-heated steam and saturated steam flowing through said passages, substantially as described.

In testimony whereof we have signed our names to this specification in the presence of two subscribing witnesses.

ROBERT BAYLES ARMSTRONG.
GEORGE PATERSON.

Witnesses:

ISABEL ROLLO,
FLORENCE HOUSTON.
